(57) **CLAIM**

The ornamental design for a vehicle fender flare, as shown and described.

DESCRIPTION

FIG. 1 is a front perspective view of an embodiment of a vehicle fender flare;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

Broken lines are used to illustrate features of the vehicle fender flare which form no part of the claimed design. Dash-dot lines indicate a boundary of claimed subject matter.
